WILLIAM MELAS, OF PHILADELPHIA, PENNSYLVANIA, ASSIGNOR OF ONE-HALF TO
DAVID TOWNSEND, OF PHILADELPHIA, PENNSYLVANIA.

OIL-BURNER.

1,169,091.

Specification of Letters Patent. Patented Jan. 18, 1916.

Application filed March 10, 1913. Serial No. 753,400.

To all whom it may concern:

Be it known that I, WILLIAM MELAS, of Philadelphia, in the State of Pennsylvania, have invented a certain new and useful Improvement in Oil-Burners; whereof the following is a specification, reference being had to the accompanying drawings.

My invention relates to burners of the class wherein liquid hydrocarbon may be mixed with a blast of another fluid serving as a diluent, for instance air, steam, oxygen or other gas, so as to be discharged, atomized and burned in combustible mixture therewith.

It is the object of my invention to govern the amount of oil which is discharged through the burner by automatically operative means within the burner; to automatically and variably limit the amount of oil discharged through the burner by and in accordance with the pressure of the diluent fluid; to automatically stop the discharge of oil, by means within the burner, if and when the diluent fluid pressure falls below a certain limit for which the burner is set; to clean the discharge orifice of the burner by relative movement of members of the burner, and automatically restore them to their original relative position, by means within the burner; to simultaneously clean any number of burners, connected to the same line, from any distance, without manipulating the burners individually; to clean the nozzle orifice of each burner, individually, independently of, and without interfering with the operation of, the others; to adjustably determine the amount of oil emitted from one or any number of burners, without interfering with the oil pressure, and without manipulating the burners; to adjustably vary the amount of oil emitted from the nozzle of any burner, independently of and without disturbing the others; to change the angle of spray, emitted by the burners, without changing the latter; to adjustably vary the amount of air emitted at a given pressure from the burner, without changing the shape or position of the discharge nozzle of the burner; by increasing or decreasing the area of the diluent fluid passage in the burner; to make the adjustments of the oil and diluent fluid discharge capacities of each burner independent of each other; and to effect double atomization of the oil, under all of the conditions of adjustment of which the burner is susceptible.

As hereinafter described my invention includes the combination with a burner casing having an axial tubular member, with an oil chamber in said member and an air chamber surrounding said member, an oil inlet communicating with said oil chamber and an air inlet communicating with said air chamber; of an oil nozzle at the inner end of said oil chamber, having an internal valve seat; an axially adjustable air nozzle at the inner end of said air chamber; a nozzle axially adjustable in said air chamber between said oil nozzle and air nozzle, having shanks extending axially in said air chamber upon opposite sides of said oil chamber, with a left hand internal screw thread at their outer ends; an annular nut engaging said nozzle screw thread, mounted to rotate, without axial movement, on said member, and having a crown clutch at its outer end; a valve fitted to said seat, having a tip fitted to reciprocate in and clean said oil nozzle, and a stem mounted to axially reciprocate in said member and having a piston sleeve rigidly connected with its outer end, mounted to axially reciprocate in said casing and having an internal right hand screw thread at its inner end; an annular nut engaged with said piston screw thread, mounted to reciprocate on said member and having a crown clutch at its inner end, adapted to engage the nozzle nut clutch aforesaid; means preventing rotation of said piston nut on said member; and a spring encircling said member, abutting against a collar at the outer end thereof and against said piston nut, tending to shift said piston and valve inward, to close the latter in opposition to fluid pressure in said air chamber. The angle of spray is variable in accordance with the axial position of said nozzle. All of the burners may be simultaneously cleaned by shutting off the air pressure; and each burner may be independently cleaned by manually pushing inward its piston, carrying its valve with the cleaning tip; said parts being automatically returned to their original position by internal air pressure on said piston.

My invention includes the various novel features of construction and arrangement hereinafter more definitely specified.

In the drawings: Figure I is an elevation 110

of a burner embodying my improvement, in connection with a spherical bearing carried by a bracket arranged to be swung to and from operative position on a furnace wall.

Fig. I^a is a transverse sectional view of said burner taken on the line A—A in Figs. 1 and II. Fig. II is a longitudinal sectional view of said burner. Fig. III is a fragmentary vertical sectional view, similar to Fig. II, but showing the oil valve in closed position. Fig. IV is a vertical sectional view, taken on the line IV, IV in Fig. II. Fig. V is a vertical sectional view, taken on the line V, V in Fig. II, but showing said oil valve in end elevation. Fig. VI is a longitudinal sectional view, similar to Fig. II, but showing a modified form of my invention. Fig. VII is a fragmentary sectional view similar to Fig. VI but showing the oil valve in open position. Fig. VIII is an outer end view of the burner casing shown in Fig. VI, showing the stuffing box and means for locking the same in adjusted position. Fig. IX is a longitudinal sectional view of a modified form of my invention. Fig. X is an outer face view of the bracket support shown in Figs. I and IX. Fig. XI is a right hand end view of said bracket support.

Referring to the form of my invention shown in Figs. I to V inclusive; the burner casing 1 has two bosses 2 and 3 respectively for the air inlet and the oil inlet, respectively communicating with the cylindrical air chamber 5 and the cylindrical oil chamber 6; said chambers being concentric with the longitudinal axis of said casing 1. Said chamber 6 extends in the core 7 which is in unitary relation with said casing 1 and screw threaded at its inner end 8 to receive the oil nozzle 9 having the cylindrical orifice 10 at the inner end of the conical valve seat 11. Said core 7 is screw threaded at its outer end to receive the core tube 13 which is rigidly held therein, as part thereof and forming therewith the tubular member of the valve casing above contemplated. The valve 15 which is fitted to said seat 11 and has the cylindrical tip 16 fitted to said orifice 10 is supported in concentric relation with said oil chamber 6 by the ribs 18 on the valve stem 19 which is fitted to reciprocate in said core extension 13 and provided with the packing 21 and stuffing box 22 therein. Said valve stem 19 has the screw thread 24 at the outer end thereof whereby it is rigidly connected with the head 25 having the wrench hold 26, conveniently a slot to fit a screw driver or similar implement. Said head 25 has the screw thread 28 whereby it is rigidly secured to the piston 29 which is prevented from outward displacement thereon by the flange 30 on said head engaging the shoulder 31 on said piston. Said piston 29 is knurled at its outer end 33, and has the internal right hand screw thread 34 at its inner end adjustably engaging the annular piston nut 35 which is fitted for axial reciprocation on said core tube 13, but prevented from turning thereon by the key 36, carried by said nut 35, extending in the keyway 37 in said core tube. Said nut 35 serves as an adjustable abutment for the inner end of the spring 40 which encircles said core tube 13 and bears at its outer end against the stationary abutment collar 41 which has the screw thread 42 rigidly engaging said core tube 13. Said spring 40 tends to shift said nut 35, piston 29, and the parts connected therewith, including the valve 15, toward the seat of the latter, against the pressure of air, or other diluent fluid, in said chamber 5. Said piston 29, being provided with the packing 45 and having the stuffing box 46 with the screw thread 47 engaging said burner casing 1, has its outward movement limited by the flange 48 on said stuffing box 46 which is opposed to the shoulder 49 on said sleeve. Said stuffing box 46 is knurled as indicated at 51 so that it may be rotated and thus axially adjusted with respect to said burner casing. It is to be understood that the position of said nut 35 is variably determined by the pressure of said spring 40 upon the outer end thereof and the pressure of the diluent fluid in the chamber 5 at the inner end thereof, but that said piston 29, and the valve 15 which is rigidly connected therewith, is axially adjustable so that it may be manually set in any desired position with respect to said valve seat 11 at any given pressure within said chamber 5; so that said piston 29 and valve 15 will assume that particular position whenever that particular pressure exists in said chamber. In other words, said valve 15 is manually adjustable with respect to its seat 11 so as to determine the area of the passageway for the oil to the oil discharge orifice 10, but is automatically controlled by the fluid pressure in said chamber 5, so that as said pressure diminishes said valve 15 is shifted toward its seat 11 by said spring 40, and closed upon its seat when said spring is no longer counterbalanced by pressure in said chamber 5. The discharge nozzle 53 is axially adjustable at the inner end of said air chamber 5, being provided with the screw thread 54 engaging the burner casing 1 and having the lock nut 55 adapted to bind against the inner end of said casing; said nozzle 53 and nut 55 being knurled to facilitate their rotation by hand. It may be observed that axial adjustment of said discharge nozzle 53 variably determines the total area of the passageway between the inner tapering surface 56 of said nozzle and the outer tapering surface of the oil nozzle 9. However, the angle of spray of the fluid mixture emitted through said nozzle 53 is 130

variably determined by the relative axial position of the nozzle 58 which is axially adjustable between said discharge nozzle 53 and oil nozzle 9; said angle of spray being 5 at its minimum when said nozzle 58 is as close as may be to the inner surface 56 of said discharge nozzle 53, and said angle being at its maximum when said nozzle 58 is as close as may be to the outer surface of 10 the oil nozzle 9. Said nozzle 58 has, as part thereof, the sectoral shanks 60 extending axially in said air chamber 5 upon opposite sides of said oil chamber 6, with a left hand internal screw thread 61 at their outer ends 15 engaging the annular nozzle nut 63 which is mounted to rotate, without axial movement, on said core member 13; axial movement of said nut 63 being prevented by the flange 64 on said core member. Said nozzle 20 nut 63 has the crown clutch 66 at its outer end, including a circular series of V-shaped teeth, opposed to a similar series of teeth, forming a crown clutch 67 at the inner end of the piston 29. It is to be understood 25 that said piston 29 may be manually thrust inward against the fluid pressure in said chamber 5, to engage the crown clutch 67 on said piston with the crown clutch 66 on said nozzle nut 63 so that, by rotation of said 30 piston 29, said nut 63 may be rotated to axially shift the nozzle 58 in either direction. Said nozzle 58 is conveniently detachably connected with its shanks 60 by the screw thread 69 and incloses the inner air 35 chamber 70 which is in communication with the outer air chamber 5 through the circular series of openings 71; so that the oil discharged through the cylindrical orifice 10 of the oil nozzle 9 is doubly atomized, first 40 by the blast of air issuing from the inner chamber 70 between said oil nozzle 9 and the nozzle 58, and second by the blast of air issuing from the outer chamber 5 between said nozzle 58 and the discharge nozzle 53; 45 both of said blasts being conical and at different angles determined by the walls between which they issue. As above noted the atomized mixture, as discharged through said nozzle 53, forms a conical spray the angle of which is determined by the relative axial position of said nozzle 58; said angle of spray being increased as the volume of air issuing between said nozzle 53 and nozzle 58 is increased, by the outward movement of said nozzle 58, to the left in Fig. II, and being diminished as the volume of air issuing between said nozzle 58, and the oil nozzle 9 is increased by the movement of said nozzle 58 in the opposite direction. 55 It may be observed that if the amount of oil being emitted through the oil nozzle 9 be increased, by withdrawing the valve 15 from its seat 11, more air is required for atomization and it is also desirable to increase the angle of spray, and to always 60 vary the angle of spray in correspondence with the amount of oil being emitted, so that the number of oil particles which pass in unit time through a unit area of a plane at right angles to the axis of the burner 70 shall be the same, whether a large or small amount of oil is emitted in unit time. Therefore, the screw thread 34 between the piston 29 and the piston nut 35 is inclined in the opposite direction to the screw thread 75 61 between the nozzle shanks 60 and the nozzle nut 63; said screw thread 34 being right hand and said screw thread 61 being left hand so that when the crown clutches 66 and 67 are engaged and rotated, by manipulation of the piston 29, both the valve 15 and the nozzle 58 will be shifted simultaneously in the same direction, to vary the angle of spray in accordance with the amount of oil being emitted. However, it 80 is to be understood that it is not essential that said screw threads 34 and 61 be respectively right hand and left hand, if they are respectively oppositely inclined; but are preferably made as described so that clockwise rotation of said piston 29 corresponds with advance movement of said valve 15 toward its seat 11. Therefore, it is to be understood that by pushing the piston 29 inward and turning it, with the crown clutches 66 and 67 engaged, the amount of oil and air being emitted in a unit of time is changed, but the ratio of air and oil remains constant, and the weight or volume of oil which passes in unit time through a unit area of a plane at right angles to the burner axis also remains constant. By simply turning said piston 29, while said clutches remain disengaged, the amount of oil being emitted in unit time is changed, and the 90 ratio of oil and air is changed; such turning movement effecting an axial movement of the valve 15 with respect to its seat, without axial movement of the nozzle 58 which determines the angle of spray as above described. By pushing said piston 29 inward, without turning it, until the cylindrical cleaner tip 16 on the valve 15 is thrust through the oil discharge orifice 10, and then releasing said piston 29, said oil nozzle 100 orifice 10 is cleaned and the parts automatically restored to precisely the same position as before the cleaning movement began. The amount of air that may be emitted through the burner at a given pressure may be variably determined by axially adjusting the discharge nozzle 53, said amount being diminished as said nozzle is shifted inwardly and vice versa. Variation 105 in the air pressure automatically effects corresponding variations in the amount of oil discharged in unit time, but does not affect the ratio of oil and air nor the spray angle. Shutting off the air automatically effects 110 the closure of the valve 15, and consequently 115 120 125 130

shuts off the oil. Therefore, groups of burners, connected to the same air supply line, may be cleaned simultaneously, without manipulation of any part of any burner, 5 by simply shutting off the air and, of course, this may be effected at a point distant from the burners. Moreover, such groups of burners may be simultaneously started or regulated at such distant point, 10 without interfering with the burners individually, by merely controlling the air pressure; and such control and adjustment of the burners in groups does not change the ratio of oil and air in any burner in such a 15 group. However, each burner is capable of independent adjustment and regulation as above set forth, and the regulation is of such a character that there is always full air pressure and full oil pressure at the 20 point of the burner nozzle. No pressure is wasted by throttling.

Said burner casing 1 is provided with the screw thread 74 by which it may be conveniently detachably supported in operative 25 relation with a furnace. As indicated in Fig. I, I find it convenient to mount said casing 1 with said screw thread 74 in connection with the spherical bearing 75 which is angularly adjustable in the socket tube 30 76 in which it may be rigidly secured by the socket nut 78. Said tube 76 is detachably connected by the screw thread 79 with the swing frame 80 hingedly connected by the pintle 81 on the bracket 82 which is secured 35 to the wall 83 by the bolts 84, so that said socket tube is in axial alinement with the fuel inlet 85 in said furnace wall. As shown in Figs. X and XI said bracket 82 has the latch 86 pivotally connected therewith by 40 the stud bolt 87 so as to detachably engage, by its hook end, the lug 88 on said swing frame 80; the arrangement being such that the burner casing 1 may be normally held in rigid relation with the furnace wall 83 but, 45 when said latch is raised, said burner may be turned, with said frame 80, away from the furnace wall 83 so that the inner end of said burner is accessible for adjustment of the discharge nozzle 53. Said bracket 82 50 has the slide bearing 89 in which the slide shutter 90 is mounted to reciprocate to the extent limited by its outwardly turned flanges 91. Said shutter has the fuel aperture 92 which, in the position shown in 55 Fig. I is presented in concentric relation with the axis of the socket tube 76 and the fuel inlet 85. However, it is to be understood that said shutter may be slid, to the left in Fig. I, so as to close said fuel inlet 60 85 in said furnace wall.

Although I prefer to embody my invention in the complex form above described, a burner constructed and arranged, in accordance with my invention, to effect the cleaning of the oil nozzle by reciprocation of the

valve without disturbing the adjustment of the burner may be made without the automatic opening and closing means, including the piston and spring, above described; for instance, as shown in Figs. VI to VIII inclusive. In said figures the burner casing is conveniently formed of two members 92 and 93 detachably connected by the screw thread 94; said member 92 being provided with the oil inlet 96 and said member 93 being provided with the air inlet 97. Said casing member 92 has in unitary connection therewith the tubular member 98 inclosing the oil chamber 99 and having at the inner end thereof the oil nozzle 100 detachably connected therewith by the screw thread 101; said nozzle having the discharge orifice 102 and the internal conical valve seat 103. The valve 105 which is fitted to said seat 103 and has the cylindrical tip 106 fitted to said orifice 102 is supported in concentric relation with said oil chamber 99 by the ribs 108 on the valve stem 109 which is fitted to reciprocate in said member 98 and provided with the valve 111 fitted to the seat 112, in said casing member 92 to shut off the flow of oil through said member 98. Said stem 109 extends through the bushing 113 in said casing member 92 and is provided with the packing 114 which is adjustable by the sleeve 115, 85 having the screw thread 116 engaging said casing member 92. Said sleeve 115 has two peripheral recesses 118, shown in Fig. VIII, either of which may be turned into registry with one of the series of complementary recesses 119 in said casing member 92 to receive the end of the spring 121 which locks said sleeve 115 in adjusted position, thus preventing its accidental rotation. Said sleeve is provided with such locking means 100 so that it may prevent accidental rotation of the valve stem 109 which reciprocates therethrough; said stem being provided with the key 123 which slides in the keyway 124 in said sleeve; the latter being provided with 110 the packing ring 125 to close the end of said keyway adjacent the packing 114. Said valve stem 109 is thus prevented from rotating in order that it may be axially shifted by rotation of the thimble 127 which is journaled in the cap 128 and provided with the screw thread 129 engaging the left hand screw thread 130 on the outer end of said valve stem 109. Said cap 128 has the screw thread 132 by which it is normally rigidly 115 connected with the casing member 92 in the position shown in Fig. VI. However, said cap is knurled as indicated at 133 so that it may be manually removed to permit adjustment of the packing 114 by rotation of said 120 sleeve 115 which is knurled at 134 to facilitate its manipulation. Said spring 121 normally presses said thimble 127 outward, with its shoulder 135 against the shoulder 136 in said cap 128, but said thimble 127 may be 130

thrust inward against the pressure of said spring 121 to reciprocate said valve stem 109 when the latter is axially shifted outward with the valve 105 in open position, for instance, as shown in Fig. VII, so that by manually pressing inward said thimble 127 the cylindrical tip 106 on the valve 105 is thrust through the orifice 102 in the oil nozzle 100 to clean said orifice; and the parts 10 are automatically restored, by the spring 121, to the axial position to which they have been adjusted by rotation of said thimble. In other words, the valve 105 may be axially adjusted with respect to its seat 103 in the 15 oil nozzle 100 by rotation of said thimble 127, and said valve 105 with its cleaning tip 106 may be manually reciprocated, to clean the oil nozzle without disturbing such adjustment. Said air inlet 97 communicates 20 with the cylindrical air chamber 138 surrounding said tubular member 98 in the casing member 93, and the volume of air flowing through said chamber, surrounding the oil nozzle 100 is variably determined by 25 axial adjustment of the air nozzle 139 which has the discharge orifice 140, concentric with said oil orifice 102, and the conical internal wall 141 extending parallel with the outer conical face of said oil nozzle 100. Said air 30 nozzle 139 has the screw thread 150 by which it is secured in said casing member 93 and is provided with the wrench hold 151 by which it may be conveniently rotated. Said air nozzle 139 may be rigidly secured in adjusted position by the jam nut 152 which 35 bears upon the inner end of said casing member 93. It may be observed that said casing member has the screw thread 154 which is like the screw thread 74 above described so that it may be connected with the 40 spherical bearing 75 shown in Fig. I.

Fig. IX shows a simpler form of my invention wherein the oil nozzle may be cleaned by reciprocation of the valve without disturbing the adjustment of the burner, and the axial position of the valve controlling the volume of oil being emitted is variably automatically determined by the air pressure in the burner. In said figure the burner casing is conveniently formed of two members 162 and 163 detachably connected by the screw thread 164, said member 162 being provided with the oil inlet 166, and said member 163 being provided with the air inlet 167. Said casing member 162 has in unitary connection therewith the tubular member 168 inclosing the oil chamber 169 and having at the inner end thereof the oil nozzle 170 detachably connected therewith by the screw thread 171; said nozzle having the discharge orifice 172 and the internal conical valve seat 173. The valve 175 which is fitted to said seat 173 and has the cylindrical tip 176 fitted to said orifice 172 is supported in concentric relation with

said oil chamber 169 by the ribs 178 on the valve stem 179 which is fitted to reciprocate in said tubular member 168 and provided with the valve 181 fitted to the seat 184 in said casing member 162 to shut off the flow of oil through said tubular member 168. Said stem 179 extends through the stuffing box 182 in said casing member 162 and is provided with the packing 183 which is adjustable by the sleeve 185 having the screw thread 186 engaging said stuffing box 182. Said valve stem 179 may be conveniently rotated by its exterior handle 188, and has the screw thread 190 engaging the piston 191 which is fitted to reciprocate in the chamber 192 in said casing member 162 and has the spring 194 thrusting it inward against the fluid pressure in said chamber 192 which is in communication with said air inlet 167, through the passageway 195 extending in said casing members 162 and 163, and the air chamber 197 in said casing member 163 surrounding said tubular member 168. It is to be understood that, during the operation of this form of my invention, the axial position of the piston 191 is variably determined by the air or other diluent fluid pressure in the burner bearing upon the inner side of said piston 191 in opposition to the pressure of the spring 194 upon the outer side thereof, and that the valve 175 is axially adjustable toward and away from its seat by rotary movement of its stem 179; so that the volume of oil being emitted through said oil nozzle 170 may be determined by manual adjustment of said valve but is automatically variable in accordance with and by variations in the air pressure in said burner effected by way of said air inlet 167 as hereinbefore contemplated. The volume of air being emitted in mixture with the oil is variably determined by axial adjustment of the air nozzle 200 which has the screw thread 201 engaging said casing member 163, and the jam nut 202 bearing upon the inner end of said member. Said air nozzle 200 has the discharge orifice 205, concentric with said oil orifice 172 and the conical internal wall 206 extending parallel with the outer conical face of said oil nozzle 170, and the latter is provided with a series of ribs 207 extending in said air chamber 197 forming a number of sectoral passage-ways for the air being emitted around said oil nozzle. It is to be understood that, by manual pressure upon said handle 188, against the fluid pressure in said chamber 192, said oil nozzle 170 may be cleaned by reciprocation of the valve 175, carrying the tip 176 through the oil orifice 172, without rotating said handle or otherwise disturbing the adjustment of the burner; said elements being automatically restored to their normal operative position, by the fluid pressure in said chamber 192, when said handle 188 is re-

leased. Said casing member 163 has the screw thread 209 which is like the screw threads 74 and 154 above described so that it may be connected with the spherical bearing 75 as shown in Fig. IX.

I do not desire to limit myself to the precise details of construction and arrangement herein set forth, as it is obvious that various modifications may be made therein without departing from the essential features of my invention as defined in the appended claims.

I claim:

1. In an oil burner, the combination with a cylindrical tubular casing having a tubular member extending axially therein, having a collar at the outer end thereof, an oil chamber in said tubular member, an air chamber surrounding said tubular member, an oil inlet communicating with said oil chamber, and an air inlet communicating with said air chamber; of a stationary oil nozzle at the inner end of said oil chamber, having an internal conical valve seat; an axially adjustable discharge nozzle at the inner end of said air chamber, in concentric relation with said oil nozzle; a nozzle axially adjustable in said air chamber between said oil nozzle and discharge nozzle, having sectoral shanks extending axially in said air chamber upon opposite sides of said oil chamber, with a left hand internal screw thread at their outer ends; an annular nozzle nut in engagement with said screw thread, mounted to rotate, without axial movement, on said tubular member and having a crown clutch at its outer end; a valve fitted to said seat, having a tip fitted to reciprocate in and clean said oil nozzle, and a stem mounted to axially reciprocate in said tubular member and having a head at the outer end thereof; a piston rigidly connected with the head on said valve stem, mounted to axially reciprocate in said burner casing, and having an internal right hand screw thread at its inner end; an annular piston nut engaged with said piston screw thread, mounted to reciprocate on said tubular member and carrying a crown clutch at its inner end, adapted to engage the nozzle nut clutch aforesaid; means for preventing rotation of said piston nut on said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
2. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; an axially adjustable discharge nozzle at the inner end of said air chamber, in concentric relation with said oil nozzle; a nozzle axially adjustable in said air chamber between said oil nozzle and discharge nozzle, having shanks extending axially in said air chamber upon opposite sides of said oil chamber, with a left hand internal screw thread at their outer ends; an annular nozzle nut in engagement with said screw thread, mounted to rotate, without axial movement, on said tubular member and having a crown clutch at its outer end; a valve fitted to said seat, having a tip fitted to reciprocate in and clean said oil nozzle, and a stem mounted to axially reciprocate in said tubular member and having a piston rigidly connected with its outer end, mounted to axially reciprocate in said burner casing; and having an internal right hand screw thread at its inner end; an annular piston nut engaged with said piston screw thread, mounted to reciprocate on said tubular member and having a crown clutch at its inner end, adapted to engage the nozzle nut clutch aforesaid; means for preventing rotation of said piston nut on said tubular member; a collar at the outer end of said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
3. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; an

- axially adjustable discharge nozzle at the inner end of said air chamber, in concentric relation with said oil nozzle; a nozzle axially adjustable in said air chamber between said oil nozzle and discharge nozzle, having a left hand internal screw thread at its outer end; an annular nozzle nut in engagement with said screw thread, mounted to rotate, without axial movement, on said tubular member and having a clutch at its outer end; a valve fitted to said seat, having a tip fitted to reciprocate in the clean said oil nozzle, and a stem mounted to axially reciprocate in said tubular member and having a piston rigidly connected with its outer end, mounted to axially reciprocate in said burner casing, and having an internal right hand screw thread at its inner end; an annular piston nut engaged with said piston screw thread, mounted to reciprocate on said tubular member and having a clutch at its inner end, adapted to engage the nozzle nut clutch aforesaid; means preventing rotation of said piston nut on said tubular member; a collar at the outer end of said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
5. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a nozzle axially adjustable in said air chamber between said oil nozzle and discharge nozzle, having an internal screw thread at its outer end; an annular nozzle nut in engagement with said screw thread, mounted to rotate, without axial movement, on said tubular member and having a clutch at its outer end; a valve fitted to said seat, having a stem mounted to axially reciprocate in said tubular member and having a piston connected with its outer end, mounted to axially reciprocate in said burner casing, and having an internal screw thread at its inner end pitched oppositely to the first named screw thread; an annular piston nut engaged with said piston screw thread, mounted to reciprocate on said tubular member and having a clutch at its inner end, adapted to engage the nozzle nut clutch aforesaid; means preventing rotation of said piston nut on said tubular member; a collar at the outer end of said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
4. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; an axially adjustable discharge nozzle at the inner end of said air chamber, in concentric relation with said oil nozzle; a nozzle axially adjustable in said air chamber between said oil nozzle and discharge nozzle, having an internal screw thread at its outer end; an annular nozzle nut in engagement with said screw thread, mounted to rotate, without axial movement, on said tubular member and having a clutch at its outer end; a valve fitted to said seat, having a stem mounted to axially reciprocate in said tubular member and having a piston connected with its outer end, mounted to axially reciprocate in said burner casing, and having an internal screw thread at its inner end pitched oppositely to the first named screw thread; an annular piston nut engaged with said piston screw thread, mounted to reciprocate on said tubular member and having a clutch at its inner end, adapted to engage the nozzle nut clutch aforesaid; means preventing rotation of said piston nut on said tubular member; a collar at the outer end of said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.

- position to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
6. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a nozzle axially adjustable in said air chamber between said oil nozzle and discharge nozzle, having means at its outer end whereby it may be axially adjusted including a clutch; a valve fitted to said seat, having a stem mounted to axially reciprocate in said tubular member and having a piston connected with its outer end, mounted to axially reciprocate in said burner casing, and having a screw thread at its inner end; a piston nut engaged with said piston screw thread, having a clutch at its inner end, adapted to engage the nozzle clutch aforesaid; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
7. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a nozzle axially adjustable in said air chamber between said oil nozzle and discharge nozzle, having means at its outer end where-

by it may be axially adjusted including a clutch; a valve fitted to said seat, having a stem mounted to axially reciprocate in said tubular member and having a piston connected with its outer end; a clutch at the inner end of said piston adapted to engage said nozzle clutch; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber; said valve being automatically closed by said spring when the latter is not counterbalanced by the fluid pressure in said air chamber.

8. In an oil burner, the combination with a casing having a tubular member with an oil chamber in said tubular member, an air chamber surrounding said tubular member, an oil inlet communicating with said oil chamber, and an air inlet communicating with said air chamber; of an oil nozzle at the inner end of said oil chamber, having a valve seat; a discharge nozzle at the inner end of said air chamber; a nozzle axially adjustable in said air chamber between said oil nozzle and discharge nozzle, having means whereby it may be axially adjusted; a valve fitted to said seat, having a stem mounted to axially reciprocate in said tubular member and having a piston connected with its outer end; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber; said valve being automatically closed by said spring when the latter is not counterbalanced by the fluid pressure in said air chamber.

9. In an oil burner, the combination with a casing having a tubular member with an oil chamber in said tubular member, an air chamber surrounding said tubular member, an oil inlet communicating with said oil chamber, and an air inlet communicating with said air chamber; of an oil nozzle at the inner end of said oil chamber, having a valve seat; a discharge nozzle at the inner end of said air chamber, between said oil nozzle and discharge nozzle, determining the angle of spray from said discharge nozzle; a valve fitted to said seat, having a stem mounted to axially reciprocate in said tubular member and having a piston connected with its outer end; and a spring tending to shift said piston and valve inward, to close the latter in opposition to fluid pressure in said air chamber; whereby, said piston is auto-

matically shifted, with said valve, relatively to said valve seat, to vary the volume of oil being emitted, in accordance with the fluid pressure in said air chamber; said valve being automatically closed by said spring when the latter is not counterbalanced by the fluid pressure in said air chamber.

10. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; an axially adjustable discharge nozzle at the inner end of said air chamber, in concentric relation with said oil nozzle; a valve fitted to said seat, having a tip fitted to reciprocate in and clean said oil nozzle, and a stem mounted to axially reciprocate in said tubular member and having a piston rigidly connected with its outer end, mounted to axially reciprocate in said burner casing, and having an internal right hand screw thread at its inner end; an annular piston nut engaged with said piston screw thread, mounted to reciprocate on said tubular member; means preventing rotation of said piston nut on said tubular member; a collar at the outer end of said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.

11. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; an axially adjustable discharge nozzle at the inner end of said air chamber, in concentric relation with said oil nozzle; a valve fitted to said seat, having a stem mounted to axially reciprocate in said tubular member and having a piston connected with its outer end, mounted to axially reciprocate in said burner casing, and having an internal screw thread at its inner end;

inner end; an annular piston nut engaged with said piston screw thread, mounted to reciprocate on said tubular member; means preventing rotation of said piston nut on said tubular member; a collar at the outer end of said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.

12. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a valve fitted to said seat, having a stem mounted to axially reciprocate in said tubular member and having a piston connected with its outer end, mounted to axially reciprocate in said burner casing, and having an internal screw thread at its inner end; an annular piston nut engaged with said piston screw thread, mounted to reciprocate on said tubular member; means preventing rotation of said piston nut on said tubular member; a collar at the outer end of said tubular member; a spring encircling said tubular member, abutting against said collar at the outer end thereof and against said piston nut, tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.

13. In an oil burner, the combination with a tubular casing having an axial tubular member with an oil chamber in said tubular mem-

- ber, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a valve fitted to said seat, having a stem mounted to axially reciprocate in said tubular member and having a piston connected with its outer end, mounted to axially reciprocate in said burner casing, and having a screw thread at its inner end; a piston nut engaged with said piston screw thread, arranged to hold said piston in axially adjusted position; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber; said valve being automatically closed by said spring when the latter is not counterbalanced by the fluid pressure in said air chamber.
14. In an oil burner, the combination with a tubular casing having an axial tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a valve fitted to said seat, having a stem mounted to axially reciprocate in said tubular member and having a piston connected with its outer end; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber; said valve being automatically closed by said spring when the latter is not counterbalanced by the fluid pressure in said air chamber.
15. In an oil burner, the combination with a casing having a tubular member with an oil chamber in said tubular member, an air chamber surrounding said tubular member, an oil inlet communicating with said oil chamber, and an air inlet communicating with said air chamber; of an oil nozzle at the inner end of said oil chamber, having an internal valve seat; a discharge nozzle at the inner end of said air chamber, in concentric relation with said oil nozzle; a valve fitted to said seat, having a stem mounted to axially reciprocate in said tubular member and having a piston connected with its outer end, mounted to axially reciprocate in said burner casing, and having a screw thread at its inner end; a piston nut engaged with said piston screw thread, arranged to hold said piston in axially adjusted position; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber, but is manually adjustable to vary the position of said valve with respect to said seat, and consequent oil emission, at any given pressure; said valve being automatically closed by said spring when the latter is not counterbalanced by the fluid pressure in said air chamber.
16. In an oil burner, the combination with a casing having a tubular member with an oil chamber in said tubular member, an air chamber surrounding said tubular member, an oil inlet communicating with said oil chamber, and an air inlet communicating with said air chamber; of an oil nozzle at the inner end of said oil chamber, having a valve seat; a discharge nozzle at the inner end of said air chamber; a valve fitted to said seat, having a stem mounted to axially reciprocate relatively to said tubular member and having a piston connected with its outer end; and a spring tending to shift said piston and valve inward, to close the latter in opposition to fluid pressure in said air chamber; whereby, said piston is automatically shifted, with said valve, relatively to said valve seat, to vary the volume of oil being emitted, in accordance with the fluid pressure in said air chamber; said valve being automatically closed by said spring when the latter is not counterbalanced by the fluid pressure in said air chamber.
17. In an oil burner, the combination with a casing having an oil inlet and an air inlet; of a discharge nozzle in communication with said air inlet; an oil nozzle in communication with said oil inlet; a valve in said oil nozzle; means whereby said valve may be axially shifted to control flow of oil through said nozzle, including a piston connected with said valve and exposed to fluid pressure in said casing tending to shift it outward, and a spring tending to shift said valve inward; and means whereby said valve may be axially shifted with respect to said piston.
18. In an oil burner, the combination with a casing having an oil inlet and an air inlet; of a discharge nozzle in communication with said air inlet; an oil nozzle in communication with said oil inlet; a valve in said oil nozzle, having exterior to said casing, means whereby said valve may be turned; a tip carried by said valve, arranged to reciprocate through said oil nozzle to clean the latter; a piston connected with said valve and exposed to fluid pressure in said casing tending to shift it outward, and a spring tending to shift said valve inward; and means whereby said valve may be axially shifted with respect to said piston.

sure in said casing tending to shift it outward; and a spring tending to shift said valve inward; whereby, said valve is normally held open by fluid pressure in said casing but said valve may be manually shifted to clean said oil nozzle.

In testimony whereof, I have hereunto

signed my name at Philadelphia, Pennsylvania, this seventh day of March, 1913.

WILLIAM MELAS.
